(57) **CLAIM**

The ornamental design for a drawer for refrigerator as shown and described.

DESCRIPTION

FIG. 1 is a front perspective view of a drawer for refrigerator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area '8' as identified in FIG. 1;

FIG. 9 is a front perspective view of the drawer for refrigerator shown in an environment of use installed in a refrigerator;

FIG. 10 is a front perspective view of the drawer for refrigerator shown in an alternate configuration of use where the upper drawer has been partially moved backward;

FIG. 11 is a front view of FIG. 10;

FIG. 12 is a back view of FIG. 10;

FIG. 13 is a left side view of FIG. 10;

FIG. 14 is a right side view of FIG. 10;

FIG. 15 is a top plan view of FIG. 10;

FIG. 16 is a bottom plan view of FIG. 10;

FIG. 17 is a front perspective view of the drawer for refrigerator shown in another alternate configuration of use where the upper drawer has been completely moved backward;

FIG. 18 is a front view of FIG. 17;

FIG. 19 is a back view of FIG. 17;

(Continued)

FIG. 20 is a left side view of FIG. 17;
FIG. 21 is a right side view of FIG. 17;
FIG. 22 is a top plan view of FIG. 17;
FIG. 23 is a bottom plan view of FIG. 17; and,
FIG. 24 is a front perspective view of the drawer for
refrigerator shown in another alternate configuration of use
where the sliding cover of the lower drawer has been
opened.

The broken lines depict portions of the drawer for refrigerator that form no part of the claimed design. The portions of FIG. 9 drawn in broken lines show environmental structure only and form no part of the claimed design. The unevenly spaced broken lines in FIGS. 1 and 8 are for the purpose of annotating the enlarged view only and form no part of the claimed design.
